CENTRALIZED TRAFFIC CONTROLLING
SYSTEM FOR RAILROADS

Thomas J. Judge, Rio De Janeiro, Brazil, assignor
to General Railway Signal Company, Rochester, N. Y.

Application March 26, 1937, Serial No. 133,224

7 Claims. (Cl. 246—3)

This invention relates to centralized traffic controlling systems for railroads, and more particularly pertains to a system of the type employing direct line wire for control of the switches and signals.

One of the objects of the present invention is to provide means for controlling a call-on signal over the same line circuit provided for the control of the main signals in a manner which 10 relates the main and call-on signals in a most desirable combination.

Other objects, purposes, and characteristic features of the present invention will be in part obvious from the accompanying drawing and in 15 part pointed out as the description of the invention progresses.

In describing the invention in detail, reference will be made to the accompanying drawing which is a diagrammatic illustration of one embodiment 20 of the present invention as applied to the control of traffic over a single railroad track switch.

Although the present invention may be applied to the control of signals associated with any type of track layout involving conflicting routes and 25 non-conflicting routes as well as various other conditions encountered in signalling practice, it has been specifically illustrated as applied to the control of the signals over a single track switch, which switch and signals are assumed to be associated with an automatic block signal system of 30 some suitable type, such for example, as disclosed in the pending application of S. N. Wight, Ser. No. 120,423, filed July 3, 1926, now U. S. Patent 2,082,436, granted June 1, 1937, although the details of such a block signalling system have not 35 been shown.

For the purpose of simplifying the illustration and facilitating in the explanation, the various parts and circuits constituting the embodiment 40 of the invention have been shown diagrammatically and certain conventional illustrations have been employed, the drawing having been made more with the purpose of making it easy to understand the principles and mode of operation, than 45 with the idea of illustrating the specific construction and arrangement of parts that would be employed in practice. Thus, the various relays and contacts have been illustrated in a conventional manner and symbols have been used to indicate 50 the connection to terminals of batteries, or other sources of electric current instead of showing all of the wiring connections to those terminals.

The symbols (+) and (—) are employed to indicate the positive and negative terminals 55 respectively of suitable batteries or other sources of

direct current; and the circuits with which these symbols are used always have current flowing in the same direction. The symbols (B+) and (B—) indicate connections to the opposite terminals of a suitable battery or other direct current source which has a central or intermediate tap designated (CN); and the circuits with which these symbols are used may have current flowing in one direction or the other depending upon the particular terminal used in combination with the 10 intermediate tap (CN). It is to be further understood that in the event alternating current should be desired, suitable means may be employed to accomplish the control by alternating current within the scope of the present invention, and 15 that the positive and negative terminals indicated by the symbols may then be considered as indicating the relative instantaneous polarities.

With reference to the accompanying drawing, a railroad track switch TS is illustrated as connecting the rails 4 of a main track to the rails 5 of a diverging or turn out track. This track switch TS is operated by a power driven switch machine SM which may be of any suitable type, such, for example, as disclosed in the patent to 20 W. K. Howe, Pat. No. 1,466,903, dated September 4, 1923, with the control of the motor of such a switch machine being preferably provided as disclosed in the patent to W. H. Hoppe et al., Pat. No. 1,877,876, dated September 20, 1932. This 25 switch machine SM may also be provided with a dual control selector to permit hand operation of the track switch as shown, for example, in the patent to W. K. Howe, Pat. No. 1,852,573, dated April 5, 1932. 30

The control of the switch machine SM is governed by a switch machine control lever SML located in a central office over a suitable line circuit arrangement properly interrelated with the signal controls as governed by the signal lever 40 SGL, all of which may be provided as disclosed in my prior application, Ser. No. 741,626, filed August 27, 1934. 35

In other words, the present invention may be considered as an improved signal control to provide for the control of a call-on signal in a manner which may be readily applied to the system shown in my above mentioned prior application, Ser. No. 741,626, filed August 27, 1934. 45

The main track adjacent the track switch TS 50 and a portion of the diverging track to the fouling point comprises a detector track circuit with the usual track battery and track relay T². The main track is also divided into certain other track sections having associated therewith the usual 55

track battery and track relays of which track relays T^1 , T^3 and T^4 are shown. Each of these track circuits is of the closed circuit type and is insulated from the rest of the track by the usual 5 insulated joints.

Traffic over the track switch TS in an east bound direction is governed by the signals $1A$ and $1B$ on the main track and onto the diverging track respectively; while signals $2A$ and $3A$ are 10 provided for governing traffic in an east bound direction on the main track and off the diverging track respectively.

A call-on signal $1C$ is provided to allow the passage of east bound traffic over either the main 15 track or the turn out track whenever the main signals governing such routes can not be cleared, due to the presence of a train in advance of such signals. Similarly, call-on signals $2C$ and $3C$ are provided to allow the passage of west bound 20 traffic over either the main track or off the turn track when the associated main signals cannot be cleared due to the presence of a train in advance of such signals.

Associated with the signal $1A$ is a home-distant 25 relay $1AHD$. Similarly, a home distant relay $1BHD$ is associated with the signal $1B$, and a home distant relay $23HD$ is associated with the signals $2A$ and $3A$. Each of these home distant 30 relays is of the usual polar neutral type and is governed in accordance with traffic conditions in advance of their respective signals in such 35 a manner that they are energized with one polarity or the other dependent upon the clear or caution indication of the next signal in advance governing traffic in the same direction, and are deenergized whenever there is intervening traffic. The control of these home distant relays has not been illustrated in detail as such control is well known to those skilled in the art and has been 40 shown, for example, in the above mentioned application of S. N. Wight, Ser. No. 120,423, filed July 3, 1926.

The track switch TS and the switch machine SM are preferably provided with point detector 45 contacts (not shown), as shown, for example, in the patent to C. S. Bushnell, Pat. No. 1,517,236, dated November 25, 1924. These point detector contacts are employed to energize a switch position indicating relay WP of the usual polar neutral type with one polarity when the track switch is in an extreme normal lock position, and to energize it with the opposite polarity when the track switch is in an extreme reverse lock position, or to deenergize this relay WP whenever 50 the track switch TS is unlocked or the switch machine SM is in operation. Such control of the relay WP is well understood and is merely indicated by a dotted line extending from the relay WP to the track switch TS and the switch 55 machine SM. In this connection it is to be understood that certain of the signal circuits illustrated herein would probably in actual practice be selected on correspondence relays instead of directly upon the relay WP, which selections have been shown in detail in my above mentioned prior application, Ser. No. 741,626, but for the 60 sake of simplicity in giving an understanding of the present invention, only the relay WP has been shown herein. However, as above mentioned, the principles of the present invention may be readily applied to the system of my prior application.

A polar neutral relay GZ of the retained type 65 is governed from the control office over a polarized control line circuit including the line wire 70

8. Such a retained-polar-neutral relay has been disclosed in the prior Pat. No. 1,852,210 dated April 5, 1932, granted to F. C. Larson. This type of relay is distinctively responsive to positive or negative energization but does not drop its neutral contacts upon a quick reversal of such polar energization by reason of the retaining winding which is inductively coupled to the main windings of the relay. Although such a relay has been employed for the purpose of disclosing the present invention, it is to be understood that various other devices and arrangements may be employed and still accomplish the purposes of the present invention. 5

Relays LD, RD and CD cooperate with the relay GZ for controlling the left, right and call-on signals respectively by selecting the circuits for signal controlling relays $1AG$, $1BG$, $1CG$, $2AG$, $2CG$, $3AG$, and $3CG$. These signal controlling relays are associated with the respective signals as indicated by their characteristic reference characters and cause their respective signals to display red or danger indications whenever the corresponding G relays are deenergized and to display green or yellow proceed indications whenever a corresponding G relay is energized only if the traffic conditions are proper. 15

Although the control of the signals has been in part illustrated and in part indicated, it is to be understood that such control may include 20 various other features so as to make the signals conventional stick signals, or signals illuminated only upon approach, or signals having some other well known feature, without departing from the scope of the present invention. It is also to be 25 understood that various features of approach locking and time release may be provided for the track switch as disclosed for example, in the prior application of R. M. Phinney, Ser. No. 463,- 30 940, filed June 26, 1930, now U. S. Patent 2,082,- 741 granted June 1, 1937. However, all such features of interrelationship between the switch TS 35 and the signals has been omitted for the sake of simplicity.

In the central office, a suitable control machine 40 is provided with the usual miniature track diagram corresponding to the track layout in the field and associated with which are the control levers. The switch control lever SML and signal control lever SGL for the track switch TS have been shown associated with the miniature 45 track switch ts. Associated with the signal lever SGL is a call-on push button CPB for providing the distinctive control of the call-on signals as hereinafter described in detail. 50

It is believed that further description of the 55 present invention from the standpoint of typical operations will best set forth its characteristic features.

OPERATION

Normal conditions.—With the various track sections unoccupied, the track relays T^1 , T^2 , T^3 , and T^4 are normally energized. The signal lever SGL is assumed to be in a central or stop position so that all of the signals are indicating stop. 60 Assuming that there is no traffic adjacent the related block sections then the relays HD are all energized with positive potential to cause their polar contacts to assume right hand positions as indicated. If a distant block signal were at caution, then the associated HD relay would be energized with negative potential, or if there is any intervening traffic, such relay HD would be deenergized by reason of the opening of track contacts in their line circuits, as will be readily ap- 65 70 75 80 85 90 95 98

parent upon consideration of the details of those circuits shown.

More specifically, the relay 1AHD is provided with a circuit from (CN), through the windings 5 of relay 1AHD, front contact 16 of track relay T², front contact 17 of track relay T³, front contact 18 of track relay T⁴, through the remaining selections to the signal next in advance to receive positive (B+) or negative (B-) potential in accordance with the clear or caution indication of such signal.

A circuit for the relay 1BHD is closed from (CN), through the windings of relay 1BHD, front contact 19 of track relay T², through the remaining 15 selections to the next signal in advance on the turn out track to receive (B+) or (B-) depending upon whether the next signal in advance is at clear or caution respectively.

The relay 23HD is energized by a circuit closed 20 from (CN), through windings of relay 23HD, front contact 20 of track relay T², front contact 21 of track relay T⁴, through the remaining selections up to the next signal in advance to receive (B+) or (B-) depending upon the clear or caution 25 indication of such signal.

Manual control of the track switch.—The track switch TS is power operated by the switch machine SM under the control of the operator by lever SML subject to proper locking to prevent 30 the track switch TS from being moved to a new position when it is unsafe to do so. For example, the track switch TS can not be operated to a new position by the operation of the lever SML whenever the signal control lever SGL has been 35 operated to a signal clearing position, nor can the movement of the lever SML to a new position under such circumstances be effective to operate the track switch when the lever SGL is restored to its stop position. In other words, the lever 40 SML must be in a position corresponding to the position of the track switch TS while the lever SGL is in its central or stop position before a new operation of the track switch TS can be effected. This has been conveniently termed the electric 45 lock equivalent and has been shown and described in my above mentioned application, Ser. No. 741,626, filed August 27, 1934. Similarly, under certain conditions the track switch TS should not be operated until a pre-determined time subsequent to the return of the governing signals to 50 stop conditions while a train is approaching such signals. To accomplish such purpose, a suitable time delay means is provided to be effective as disclosed in the above mentioned prior application of R. M. Phinney, No. 463,940, filed June 26, 1930.

All of these features are well known to those skilled in the art, but have been mentioned in connection with the present disclosure for the purpose of bringing out the purpose and utility 60 of the call-on signals of the present invention.

Main signal control.—With the track switch TS in a normal position for the passage of main line traffic, either the signal 1A or the signal 2A can be cleared depending upon whether the signal 65 control lever SGL is actuated to the right or to the left respectively.

When the lever SGL is operated to the right, the signal control line circuit is energized with energy from (B-), through a circuit including 70 front contact 30 of call-on push button CPB, signal control lever contact 6 in a left hand position, windings of relay G2Z, line wire 8, front contact 31 of track relay T², windings of relay GZ, to (CN).

75 Such energization of the relay GZ causes its

polar contacts to be operated to the left followed by the picking up of its neutral contacts. This closes an energizing circuit for the signal control relay RD from (+), through a circuit including front contact 32 of relay GZ, polar contact 33 of 5 relay GZ in a left hand position, back contact 34 of relay LD, windings of relay RD, to (-).

As soon as the relay RD picks up, it closes a stick circuit from (+) through a circuit including a front contact 32 of relay GZ, front contact 35 10 of relay RD, windings of relay RD, to (-).

The picking up of the relay RD completes an energizing circuit for the relay 1AG from (+), through a circuit including polar contact 36 of 15 relay GZ in a left hand position, front contact 37 of relay RD, back contact 38 of relay CD, front contact 39 of relay WP, polar contact 40 of relay WP in a right hand position, front contact 41 of relay 1AHD, windings of relay 1AG, to (-).

The picking up of the contact 42 of relay 1AG 20 causes the signal 1A to change its indication from stop to clear or caution depending upon the position of polar contact 43 of the relay 1AHD. It is readily apparent that this signal 1A may be returned to stop by restoring the lever SGL to its 25 central position.

If the lever SGL is operated to the left, relay GZ is energized over a circuit closed from (B+), through a circuit including front contact 44 of 30 call-on push button CPB, lever contact 6 in a right hand position, windings of relay G2Z, line wire 8, front contact 31 of track relay T², main windings of relay GZ, to (CN).

Such energization causes the polar contacts of 35 the relay GZ to operate to the right and followed by the picking up of its neutral contacts. This closes an energizing circuit for the relay LD from (+), through a circuit including front contact 32 of relay GZ, polar contact 33 of relay GZ in a right hand position, back contact 45 of relay RD, 40 windings of relay LD, to (-).

As soon as the relay LD picks up, it closes a stick circuit from (+), through a circuit including front contact 32 of relay GZ, front contact 46 of 45 relay LD, windings of relay LD, to (-).

The picking up of the relay LD closes an energizing circuit for the relay 2AG from (+), through a circuit including polar contact 36 of 50 relay GZ in a right hand position, front contact 47 of relay LD, back contact 48 of relay CD, front contact 49 of relay WP, polar contact 50 of relay WP in a right hand position, front contact 51 of relay 23HD, windings of relay 2AG, to (-).

The picking up of contact 52 of relay 2AG 55 causes the signal 2A to change its indication from stop to clear or caution depending upon the position of polar contact 53 of relay 23HD.

It is, of course, obvious that the return of the lever SGL to a central position causes the return of the signal 2A to stop.

Assuming that the track switch TS has been operated to a reverse position which is indicated by the proper responses of relay WP, then either the signal 1B or the signal 3A may be cleared by the actuation of the lever SGL to the right or to 65 the left respectively.

If the lever SGL is operated to the right under such circumstances, then the relay GZ is energized with negative potential, as above described, causing the relay RD to be picked up. This causes 70 the energization of the relay 1BG by a circuit closed from (+), through a circuit including polar contact 36 of relay GZ in a left hand position, front contact 37 of relay RD, back contact 38 of relay CD, front contact 39 of relay WP, 75

polar contact 40 of relay WP in a left hand position, front contact 54 of relay 1BHD, windings of relay 1BG, to (-).

The picking up of contact 55 of relay 1BG causes the indication of the signal 1B to change from stop to clear or caution depending upon the position of the polar contact 56 of the relay 1BHD.

It is, of course, apparent that the signal 1B can be returned to stop by the restoration of the signal lever SGL to its central or stop position.

If the lever SGL is operated to the left with the track switch TS in a reverse position, then the relay GZ is energized with positive potential, 15 as above described, so that the relay LD is picked up. This closes an energizing circuit for the relay 3AG from (+), through a circuit including polar contact 36 of relay GZ in a right hand position, front contact 47 of relay LD, back contact 48 of relay CD, front contact 49 of relay WP, polar contact 50 of relay WP in a left hand position, front contact 51 of relay 23HD, windings of relay 3AG, to (-).

The picking up of contact 58 of relay 3AG causes the signal 3A to change its indication from stop to clear or caution depending upon the position of the polar contact 59 of relay 23HD.

It is, of course, obvious that the signal 3A may be returned to stop by the return of the signal lever SGL to its central or stop position.

Call-on signal control.—There are times when a first train, as a west bound train, is beyond a main signal, such as signal 2A, for example, a sufficient distance to allow a second, west bound, 35 train to pass over the track switch TS, and then make a back up move onto the turnout track without waiting for the first train to pass beyond the next signal in advance. Obviously, in a centralized traffic controlling system where trains are entirely governed by signal indication, such second train could not proceed over the track switch because the signal 2A can not be cleared with relay 23HD deenergized by reason of the occupied condition of the track section including 45 relay T¹. But the present invention provides that a call-on signal 2C under such circumstances may be cleared by proper manipulation of the signal lever SGL and call-on push button CPB.

Assuming such circumstances, the operator 50 would move the signal lever SGL to its left hand position and noting that the main signal does not clear by reason of the failure of a suitable signal indication for signal 2A to be displayed on the control panel (by means not shown but contemplated as employed in connection with the present invention as disclosed in my prior application No. 741,626), he then momentarily operates the call-on push button CPB followed by its self-restoration to its normal position.

55 While the call-on push button CPB is actuated, the original positive polarity (B+) placed upon the signal control line circuit through front contact 44 of push button CPB is reversed so that negative potential is applied through back contact 44. Such reversal of polarity on the relay GZ causes it to actuate its polar contacts to left hand positions, but as this reversal is accomplished relatively fast, the neutral contacts of the relay GZ remain picked up.

60 The actuation of the signal lever SGL to the left and the initial energization of the relay GZ caused the relay LD to be picked up with the polar contact 33 in a right hand position, but such relatively quick reversal of the polarity on the 65 relay GZ by button CPB causes the polar contact

33 to be actuated to the left although the neutral contact 32 of the relay GZ is still picked up maintaining the stick circuit of the relay LD.

Thus, as soon as the polar contact 33 reaches a left hand position, a pick up circuit is closed for the relay CD from (+), through a circuit including front contact 32 of relay GZ, polar contact 33 of relay GZ in a left hand position, front contact 34 of relay LD, windings of relay CD, to (-). The relay CD immediately picks up closing 10 a stick circuit from (+), through a circuit including front contact 32 of relay GZ, front contact 63 of relay CD, windings of relay CD, to (-).

Upon the release of the push button CPB, the polarity on the relay GZ restores to the original 15 polarity applied by the lever SGL in a left hand position, but the relatively quick reversal occurs without dropping the neutral contact 32 of the relay GZ so that both the relays LD and CD are maintained picked up through their stick circuits.

The picking up of the relay CD closes an energizing circuit for the relay 2CG from (+), through a circuit including polar contact 36 of relay GZ in a right hand position, front contact 47 of relay LD, front contact 48 of relay CD, front contact 61 of relay WP, polar contact 62 of relay WP in a right hand position, back contact 63 of relay 2AG, windings of relay 2CG, to (-).

The picking up of contact 64 of relay 2CG 30 causes the signal 2C to change its indication from stop to clear so that the train may pass over the track switch TS subject to the rules or instructions given to trainmen with regard to proceeding on permission of a call-on signal, such as, for example, being prepared to stop upon sight of an obstruction.

After the train has passed over the track switch TS and beyond the signal 1A, the track switch TS may be caused to operate to a reverse 40 position so that the train may proceed in accordance with the indication of signal 1B or signal 1C onto the turn out track.

It will be noted in connection with the above description, that the call-on signal 2C cannot 45 be cleared unless the signal 2A is at stop by reason of the inclusion of the back contact 63 of relay 2AG in the energizing circuit of the relay 2CG, but once the call-on signal is cleared such call-on signal is entirely under the control of the operator and the signal 2A cannot in any way 50 automatically clear upon the passage of the first train beyond the governing block section. This is because of the open condition of the circuit for relay 2AG at back contact 48 of relay CD.

It is also noted that a call-on signal can not 55 be cleared unless the operator first endeavors to clear the corresponding main or high speed signal by the proper manipulation of the lever SGL, (and if the main signal is not held at stop by 60 traffic, it may clear, but a long operation of the push button CPB, relay CD picks up, to cause the main signal to go to stop) and the continued clear condition of a call-on is dependent upon the signal lever SGL remaining in this main signal clearing position, while the putting to stop of either a main or call-on signal is accomplished by the same operation, namely, the return of the lever SGL to its stop position.

It will be readily apparent that the picking up 70 of the relay CD by the operation of the call-on push button CPB while the signal lever SGL is in a left hand position with the track switch TS in a reverse position causes the energization of the relay 3CG by reason of a circuit closed from 75

(+), through a circuit including polar contact 36 of relay GZ in a right hand position, front contact 47 of relay LD, front contact 48 of relay CD, front contact 61 of relay WP, polar contact 5 62 of relay WP in a left hand position, back contact 65 of relay 3AG, windings of relay 3CG, to (-). The picking up of contact 66 of relay 3CG changes the indication of the signal 3C from stop to clear. It is, of course, obvious that the 10 return of the signal lever SGL to its stop position restores such signal to stop.

There is another condition under which a call-on signal is particularly useful in connection with the remote control of trains by signal indication. For example, a first train may be standing upon the track section associated with relay T³ so that the home distant relay 1AHD is de-energized opening front contact 41. This prevents the operator from clearing the signal 1A 15 to allow a second train to proceed past such signal to connect with the first train. In fact, it would be undesirable to clear a high speed signal, such as signal 1A, with a train standing on such track section, but the clearing of the call-on 20 signal 1C with its limited speed restrictions, readily permits a second train to proceed past signal 1C to connect with the first train standing on the track section T³.

Let us assume that the operator actuates the 30 signal lever SGL to the right while a first train is on the track section associated with relay T³. This causes negative potential to be applied to the relay GZ actuating its polar contacts to the left and picking up its neutral contacts so that 35 the relay RD is picked up, but the relay 1AG can not be picked up for reasons above pointed out, namely, the open condition of front contact 41. The operator then actuates the call-on push button CPB, momentarily reversing the polarity 40 applied to the relay GZ to close a circuit for the relay CD from (+), through a circuit including front contact 32 of relay GZ, polar contact of relay 33 in a right hand position, front contact 45 of relay RD, windings of relay CD, to (-). As soon as the relay CD is picked up, its stick circuit is closed so that the release of the push button CPB and the consequent reversal of polarity 45 on the relay GZ do not effect the dropping of either RD or CD, but does accomplish the clearing 50 of the call-on signal 1C by the energization of the relay 1CG over a circuit closed from (+), through a circuit including polar contact 36 of relay GZ in a left hand position, front contact 55 31 of relay RD, front contact 38 of relay CD, front contact 67 of relay WP, back contact 68 of relay 1AG, back contact 69 of relay 1BG, windings 60 of relay 1CG, to (-). The picking up of contact 70 of relay 1CG changes the indication of the signal 1C from stop to clear. It is, of course, obvious that the return of the signal lever SGL to its center or stop position causes the relay 1C to be returned to stop.

It is noted that in order to pick up the relay 65 1CG to clear the signal 1C, both of the signals 1A and 1B must be at stop by reason of back contacts 68 and 69 of relays 1AG and 1BG respectively. Also, the track switch TS must be locked as indicated by the energized condition and closure of front contact 67 of relay WP, 70 although the call-on signal 1C may be cleared with the track switch TS in either normal or reverse position.

Under each of the conditions above assumed for the clearing of a call-on signal, it is apparent 75 that the main signal is held at stop automatic-

ally by the presence of a train, but if there is no train to hold the main signal at stop, the operation of the call-on push button CPB causes such main signal to be put to stop and the call-on signal to be cleared by reason of the picking up of the relay CD.

It is also being noted in connection with the control of call-on signals that a double reversal of polarity is required in order to clear a call-on signal. In other words, a single reversal of 10 polarity results in the clearing of no signal at all. For example, should the operator actuate the signal lever SGL to the right and then changing his mind quickly operate it to the left, a quick reversal of polarity would occur on the relay GZ 15 but such reversal of polarity would first pick up the relay RD and then the relay CD, but the relay GZ would then be energized with positive potential so that its contacts would be to the right, so that it would result in clearing no signal. In 20 brief, the polarity required on the relay GZ in order to clear a signal must be the initial polarity and the double reversal is required in order to accomplish this. This feature also provides that the operator can not ill-advisedly hold the button CPB down while he actuates the lever SGL to the right or to the left and thereafter release the relay CPB and obtain a call-on signal. He will neither get the call-on nor the main signal 25 in such a circumstance.

Track indication.—The signal control line circuit includes front contact 31 of the track relay T² so that the signal can not be cleared while a train is on the detector track section and also provides for means whereby the presence or passage of a train over the detector track section 30 can be indicated in the central office.

More specifically, whenever the signal lever SGL is in an operated position to clear a signal and a train accepts such cleared signal, then the 40 opening of contact 31 deenergizes the relay G2Z. Such deenergization of the relay G2Z can be employed to provide control for a track occupancy indicator in any suitable way, as shown for a similarly designated relay in my prior application 45 No. 741,626, filed August 27, 1934, as well as for the other purposes disclosed in such prior application. The contacts 12 and 29 of relay G2Z correspond respectively to the contacts with the same reference characters in such prior application 50 to which reference may be made for a typical control for providing such an indication.

In this connection, it is to be noted that the features of the present invention are assumed to be applicable as an improvement upon the 55 system of the prior application so that with the circuit arrangements disclosed therein modified in accordance with the present invention, the operation of the relay G2Z in combination with the operations disclosed in such prior application may readily accomplish the purposes disclosed therein. However, it is thought to be sufficient for an understanding of the present invention and the manner in which an electro-responsive means may act in the central office for the control of suitable indicators and the like to merely indicate by a legend on the drawing that the relay G2Z may accomplish the control of a track occupancy indicator in any suitable manner known in the art. In other words, such control 60 of an indicator need not be the same as shown in my prior application but may be as shown in the patent, No. 1,794,594, granted March 3, 1931, to F. L. Dodgson.

Although only one specific embodiment of the 75

invention has been disclosed and although it has been mentioned that the principles of the present invention may be applied to the system of my prior application No. 741,626, it is to be understood that the principles of the present invention may be applied to various other types of systems where the polarized line circuit is employed for the control of the signals.

Having described a traffic controlling system as one specific embodiment of the present invention, it is desired to be understood that this form is selected to facilitate in the disclosure of the present invention, rather than to limit the number of forms which it may assume, and it is to be further understood that various modifications, adaptations and alterations may be applied to the specific form shown to meet the requirements of practice without in any manner departing from the spirit or scope of the present invention, except as limited by the appended claims.

Having described my invention, I now claim:

1. In a centralized traffic controlling system for railroads; a main signal and a call-on signal; a retained-neutral-polar relay controlled over a polarized line circuit; a main signal relay; a call-on signal relay; a pick-up circuit for said main signal relay closed when said retained-neutral-polar relay is energized with one polarity; a stick circuit for said main signal relay including a front contact of said main signal relay and a front contact of said retained-neutral-polar relay; a pick-up circuit for said call-on signal relay including a front contact of said main signal relay and a front contact of said retained-neutral-polar relay; a control circuit for said main signal including a front contact of said main signal relay and a polar contact of said retained-neutral-polar relay closed when said retained-neutral-polar relay is energized with said one polarity; and a control circuit for said call-on signal including a front contact of said main signal relay, a front contact of said call-on signal relay, and a polar contact of said retained-neutral-polar relay closed when said retained-neutral-polar relay is energized with said one polarity.

2. In a centralized traffic controlling system for railroads, a railroad track switch, main signals for controlling traffic over said track switch in both of its positions for both directions, call-on signals for controlling traffic over said track switch in both of its positions for both directions, a line circuit extending from said track switch to a control office, a control lever at the office for energizing said line circuit with one polarity or the other and for deenergizing said line circuit, a manually operable push button for causing a double reversal in polarity of the energization of said line circuit as determined by said control lever, a retained-neutral-polar relay included in series in said line circuit at said track switch, circuit means for clearing the particular main signal for the route determined by the position of the switch for one direction when said retained-neutral-polar relay is energized with one polarity, circuit means for energizing the particular main signal for the route determined by the position of the switch for the opposite direction when said retained-neutral-polar relay is energized with the opposite polarity, and circuit means for clearing the particular call-on signal for the

route determined by the position of the switch for one direction or the other in accordance with the initial polarity of energization of said line circuit as repeated by said retained-neutral-polar relay only after a double reversal in polarity of the energization of said line circuit with said reversals each occurring sufficiently quickly to maintain closed the front contact of said retained-neutral-polar relay.

3. In a centralized traffic controlling system for railroads, a main signal and a call-on signal, a control office, a line circuit connecting said signals with the control office, relay means for controlling said main signal to indicate clear and stop, respectively, by energization and deenergization of said line circuit, and means for clearing said call-on signal by only a double reversal in polarity of the energization of said line circuit when the separate reversals are effected without leaving the line deenergized a period of time as long as the operating time of part of said relay means, said signals requiring continued energization of the line circuit for their continued indication.

4. In a centralized traffic controlling system for railroads, a control office, a line circuit connecting the control office with a remote location, two traffic controlling devices at the remote location, means for energizing and deenergizing one of said devices by energization and deenergization respectively of said line circuit, and means for energizing the other of said devices by only a double reversal in polarity of the energization of said line circuit, and with each reversal effected without leaving the line deenergized for more than a predetermined time, said devices requiring continued energization of the line circuit for their continued energization.

5. In a centralized traffic controlling system for railroads, a control office, a line circuit connecting the control office with a remote station, two traffic controlling devices at the remote station, a control lever at the office for energizing said line circuit with current of one or the other polarity or deenergizing said line circuit, other control means at the office for causing a relatively quick double reversal in polarity of the energization of said line circuit as determined by said lever, electro-responsive means at the station responsive to the energization and the deenergization of said line circuit for respectively distinctively controlling one of said traffic controlling devices, the electro-responsive means being slower to respond to deenergization of the line circuit than the time required during each of said double reversal of polarity when the line circuit is deenergized, and means at the station controlled by said electro-responsive means in response to a double reversal in polarity of the energization of said line circuit for controlling the other of said traffic controlling devices.

6. In a centralized traffic controlling system for railroads, a group of signals, means for selectively controlling the signals by the distinctive polarized energization of a retained-neutral-polar relay, manual means for controlling the energization of the relay, other traffic controlling means, and control circuits for said other means operative only upon a double reversal in polarity of the energization of said retained-neutral-polar relay when the deenergized periods of the retained-neutral-polar relay occurring upon each said reversal is less than the releasing time for such polar relay, said signals all becoming de-

energized upon the polar relay becoming deenergized for a time equal to its releasing time.

7. In a centralized traffic controlling system for railroads, a control office, a main signal and a call-on signal for governing traffic over a stretch of track, a line circuit extending between said signals and the control office, slow acting means for distinctively controlling said main signal by energization and deenergization respectively of said line circuit, means including said slow acting means for controlling said call-on signal by only a double reversal in polarity of the energization of said line circuit, with the deen-

ergization period of the line circuit occurring upon each said reversal not continuing as long as the time for the slow acting means to respond to a deenergization, deenergization of the line circuit for a time as long as the time for the slow acting means to respond to a deenergization deenergizing the signals, and means for indicating in the control office the entrance of a train into said stretch of track by deenergization of said line circuit at a time when such line circuit is energized to control either said main signal or said call-on signal. 5 10

THOMAS J. JUDGE.
